UNITED STATES PATENT OFFICE.

JAMES T. COWLEY, OF SYRACUSE, NEW YORK, ASSIGNOR TO THE LAMSON COMPANY, OF SYRACUSE, NEW YORK, A CORPORATION OF MASSACHUSETTS.

POWER CONTROLLER.

Application filed April 25, 1925. Serial No. 25,765.

This invention pertains to power controllers for pneumatic despatch systems and relates more particularly to automatically actuated controllers of the so-called minimum flow type of which the patent to Libby No. 968,578, August 30, 1910, furnishes a familiar example.

Controllers of this type comprise essentially a valve located between the transmission tube and an air exhauster or vacuum drum, such valve normally cutting off carrier propelling air flow through the tube when the tube is idle, although there is at all times permitted a continuous air flow of relatively small volume, insufficient to propel a carrier, and known as the "minimum flow", and a pneumatic, for example a piston or diaphragm, which responds, either directly or indirectly, to change in pressure in the tube, due to the momentary cutting off or checking of the minimum flow of air incident to the insertion of a carrier in the tube, and which by such response opens wide the valve to permit a full carrier propelling air flow through the transmission tube.

In the form of apparatus described in the Libby patent the period during which the valve remains open is determined solely by the operation of a timing device. The present invention is intended to improve the operation of devices of this general type by eliminating the timing device and in place thereof providing means which is responsive directly to the change in pressure in the transmission tube, incident to discharge of the last carrier therefrom, for initiating closure of the controlling valve. In accordance with the present invention such response of the pneumatic to discharge of the carrier results indirectly in equalizing the pressure upon opposite sides of such pneumatic thereby permitting closure of the controlling valve by means of a spring or other device.

In the accompanying drawings a preferred embodiment of the invention is illustrated by way of example.

Fig. 1 being a diagrammatic elevation, partly in section, showing the improved controller installed between one transmission tube of a pneumatic system and the exhaust header thereof;

Fig. 2 being a vertical section to large scale showing the parts in normal position, the main valve being closed; and

Fig. 3 being a view similar to Fig. 1 but showing the parts as positioned at the instant after discharge of the last carrier from the tube but before the main valve has closed.

Referring to Fig. 1 of the drawings, the numeral 1 indicates a portion of a central station desk provided with the despatch terminal 2 forming a part of the sending transmission tube 3 leading to an outlying station. The corresponding return transmission tube 4 is provided with the usual delivery terminal 5 and with an extension 6 which passes down through the top of the desk 1 and is connected with the power control apparatus indicated generally at 7. A suction tube 8 leads from the power control apparatus to the usual section drum or header 9 in which a vacuum is constantly maintained by means of a suitable exhauster, not shown. A continuous air passage or conduit is thus provided extending from the terminal 2, to the exhauster, that portion of the conduit provided by the tubes 3 and 4 constituting the carrier transmission line.

Referring to Figs. 2 and 3 the numeral 7 as above explained indicates the improved power controller as a whole. This controller in the embodiment illustrated comprises a hollow casing 10 having therein a chamber 10^a which communicates freely at all times with the pipe 8 leading to the suction header 9. A substantially U-shaped partition or septum 11, comprising substantially parallel upper and lower walls 12 and 13 respectively, separates the main body of the chamber 10^a from an inlet chamber 14 which communicates directly with the tube 6.

The upper and lower walls 12 and 13 of the septum 11 are furnished with aligned valve orifices 15 and 16 respectively. A valve 17 of balanced type hereinafter referred to as the main valve, comprising spaced heads 18 and 19, cooperates with the orifices 15 and 16 and controls the inward flow of air through the transmission tubes 3 and 4 toward the exhaust header 9. Normally the valve 17 is closed so as to cut off carrier propelling air flow through the

transmission line but at all times a small continuous flow of air through the transmission line is permitted by the provision of a conduit 20 leading directly from the 5 pipe 6 to the pipe 8 outside of the controller casing 10. While such an outside pipe is preferred, similar results may be obtained if desired by providing a small orifice through one of the walls of the septum 11, 10 by making the valve heads 18 and 19 somewhat smaller than the valve orifices so as to allow leakage of air past the valve heads, or by spacing the valve heads when in closed position, from the seats.

15 The upper wall 21 of the controller casing 10 is flared outwardly and upwardly to provide a shallow receptacle 22 of generally circular contour which has a radial flange 23 at its edges. This flange forms a 20 seat for the outer edge of a flexible diaphragm 24 which is clamped against the flange 23 by the marginal flange 25 of a downwardly concave cover member 26 which may be secured to the flange 23 in any desired manner, for example by means 25 of bolts, not shown. The members 22 and 26 thus constitute a pneumatic main motor casing which is divided by the diaphragm 24 into upper and lower chambers 27 and 28 respectively. The lower chamber 28 communicates freely at all times with the outer air by means of one or more large orifices 29 in the member 22 while the chamber 27 communicates with the atmosphere by means of a single very small orifice 29a 30 preferably controlled by an adjustable needle valve.

The central part of the diaphragm is 40 preferably stiffened by means of clamping plates 30 and 31 disposed upon its opposite sides and is secured to the upper end of the stem 32 of the main valve 17 by means of a bolt 33 which passes through the plates 30 and 31 and the central part of the diaphragm and has threaded engagement with an axial opening in the stem 32. For convenience in assemblage of the parts it is preferred to provide the upper wall 21 of the casing 10 with a central aperture which 45 is normally covered by a removable plate 34 having a boss 35 provided with a guideway for the stem 32 of the valve.

50 A rod 36, forming an extension of the stem 32, has screw-threaded engagement at its lower end with a threaded opening in the head of the bolt 33. This rod 36 passes through a guide opening in the upper end of a gland 37 having threaded engagement with an opening in a boss 38 projecting 55 from the cover 26. One end of a compression spring 39 bears against the inner surface of the gland 37. This spring encircles the rod 36 and bears at its lower end against a collar 40 secured to the rod 36. By 60 screwing the gland 37 in or out the tension

of the spring 39 may be varied, the tendency of the spring being to depress the diaphragm 34 and retain it in the normal position indicated in full lines in Fig. 2. The upper end of the rod 36 is screw-threaded at 41 for 65 the reception of an adjustable contact thimble 42.

The cover 26 is provided at one side with an upstanding boss 43 which forms a support for the case of an auxiliary motor pneumatic 70 comprising the lower saucer-like receptacle 44 having a radial flange 45 at its edge which forms a seat for the edge of an flexible diaphragm 46. The edge of the diaphragm is clamped between the flange 45 and the flange 75 47 of the downwardly concave cover member 48 of the auxiliary motor case.

The central part of the diaphragm 46 is 80 preferably clamped between the stiffening plates 49 and is provided with a two-part 85 stem comprising an upwardly extending member 51 and the downwardly extending member 50. The members 50 and 51 have threaded engagement with each other at their opposed ends and clamp the plates 49 90 between them.

The member 50 of the stem, is furnished with a restricted axial passage 53 of small cross section which opens laterally through the side of the stem at the point 54, outside 95 of the auxiliary motor casing, and also at the point 55 within the casing and above the diaphragm 46.

A valve disk 56 is secured to the lower end of the stem member 50 and cooperates with 100 an annular valve seat 57 defining a large valve orifice 58 opening into the chamber 27 of the main motor and normally connecting said chamber through passages 59 and 60 with the chamber 14 and the transmission 105 tube extension 6.

The stem member 51 slides in a guide opening in gland 61 having threaded engagement with a boss 62 upon the cover member 48 of the auxiliary motor casing and 110 is provided at its upper end with an adjustable contact member 65. A coiled spring 63 bears at its upper end against the inner surface of this gland while the lower end of the spring bears against a flange 64 upon 115 the lower end of the stem member 51. The spring thus tends to depress the diaphragm 46 and to restore it to the normal position indicated in Fig. 2. By turning the gland 61 the tension of the spring may be varied. 120

A bracket 66 is secured to the cover member 48 of the main auxiliary motor and forms a support for a pivot pin 67 constituting the fulcrum for a lever 68. This lever is pivoted to swing in the plane defined by the parallel stem members 36 and 51 of the main and auxiliary diaphragms respectively and at its end 69 is guided by 125 passing through a vertical slot 70 in a bracket member 71 secured to the cover 48. The slot 130

70 is closed at its upper end as indicated at 70^a to form a limiting abutment for the end of the lever 69. This end of the lever is normally held against said abutment by a 5 spring 73. One end of the spring is secured to the end 72 of the lever, its other end being attached to an eye bolt 74 passing through a suitable opening in the flanges 23 and 25 and having an adjustable nut 75 10 at its lower end.

The operation of the device is substantially as follows; it being assumed that when the transmission tube is idle the parts occupy the position indicated in full lines in Fig. 2. 15 When in this position the contact members 42 and 65 are both spaced from the lower edge of the lever 68. Under these conditions a minimum flow of air enters through the open transmission terminal 2 of the tube 20 20 3 and passes through the outlying station, tube 4, pipe 6 and tube 20 to the exhaust. 25

When a carrier is inserted in the transmission tube either at the point 2 or at the outlying station, this minimum flow is cut off or substantially diminished with a resultant increase in the vacuum in the transmission line. This decrease in pressure is immediately transmitted through the passage 59 and the open valve orifice 58 to the 30 chamber 27 where it is effective to raise the diaphragm 24 against the resistance of the spring 39 and thus to open the main valve 17. As soon as the main valve begins to open the vacuum in the transmission tube is 35 further increased so that the diaphragm 24 rises with increasing force until the main valve is fully open. As the main valve approaches its fully open position the contact member 42 engages the lower edge of the 40 lever 68 and tilts the latter to the dotted line position indicated at 76 in Fig. 2, thus tensioning spring 73. This moves the end 69 of the lever downwardly and brings the lower edge of the lever into substantial engagement with the contact member 65 of the 45 valve stem 51.

While the above operations have been taking place the decreased pressure in the passage 59, due first to insertion of the carrier, 50 and second to opening of the main valve, is slowly transmitted through the passage 53 to the upper chamber 48^a of the auxiliary motor. As the lower chamber 48^b of this motor is always freely open to the atmosphere through a vent 44^a the diaphragm tends to rise; but as the pressure in the chamber 48^a drops much more slowly than that in the chamber 27 of the main diaphragm the latter has time to rise to its uppermost position before the vacuum in the chamber 48^a is sufficient to overcome the spring 63. When the vacuum in the chamber 48^a finally becomes great enough to overcome the spring 63 the upward movement of 55 the diaphragm is prevented by engagement 60

of the contact member 65 with the lever arm 69. The parts thus remain in this position with the valve orifice 58 wide open so long as a carrier remains in the transmission tube. 70

When the last carrier emerges from the transmission tube the vacuum in the transmission tube slightly decreases by reason of the removal of the frictional drag of the carrier in passing along the tube. This slight increase in pressure in the transmission tube permits the diaphragm 24 to move down to a slight extent responsive to its spring 39, assisted by the spring 73, until the lever 68 is restored to its normal substantially horizontal position as indicated in Fig. 3. As the vacuum in chamber 48^a is already sufficient to lift the diaphragm 24 against the resistance of spring 63, this diaphragm immediately rises and closes the valve 56 against its seat 57. Since the valve chamber 27 is now no longer connected to the transmission tube and exhaust, atmospheric air leaks in through the aperture 29 until the pressure upon opposite sides of the diaphragm 24 has been equalized whereupon the spring 39 depresses the diaphragm 24 and closes the valve 17 thus cutting off the carrier propelling air flow through the transmission tube. 93

As soon as such flow is cut off the pressure in the chamber 48^a begins slowly to rise as air leaks in through the passage 53 and after a short interval the spring 63 restores the valve 56 to its normal open position. 100

By the arrangement thus described the opening of the main valve is accomplished automatically by the slight drop in pressure in the transmission tube incident to introduction of a carrier and such valve is positively held open until the last carrier emerges from the line. The slight increase in pressure incident to delivery of the last carrier then initiates closure of the main valve. The device thus operates independently of any timing arrangement and solely in accordance with the presence or absence of a carrier or carriers from the transmission tube. 105 110

While I have herein illustrated a preferred embodiment of the invention I wish it to be understood that various changes in relative position and proportion of parts as well as the substitution of equivalents for the elements herein described as forming the combination may be made without departing from the spirit of the invention; and in my copending application Serial No. 25,766 filed April 25, 1925, I have disclosed and claimed a modified arrangement for determining the time of closure of the auxiliary valve. 115 120 125

I claim:

1. Pneumatic despatch apparatus comprising a conduit and an exhaust connected 130

ed therewith, a controlling valve located in the conduit, a minimum flow of air through the conduit being permitted when the valve is in closed position, a motor pneumatic for opening said valve when a carrier is inserted in the conduit, one side of said pneumatic normally being exposed to transmission tube pressure, said pneumatic holding the valve wide open so long as a carrier remains in the conduit, and means acting automatically upon delivery of the last carrier from the tube to cut off transmission line pressure from the pneumatic whereby to initiate closure of the valve.

15. Pneumatic despatch apparatus having a transmission tube, an exhauster connected therewith, and a valve for controlling the flow of air through the transmission tube, a minimum flow of air through the tube being permitted when the valve is in closed position, a pneumatic normally exposed to transmission tube pressure, said pneumatic responding to decrease in pressure in the tube incident to insertion of a carrier in the latter whereby to open the controlling valve, said pneumatic also responding to pressure change in the tube incident to discharge of the last carrier from the latter, and means actuatable by said pneumatic when responding to such last named pressure change for initiating the cutting off of such transmission tube pressure from the pneumatic.

30. Pneumatic despatch apparatus having a transmission tube, an exhauster connected therewith and a valve for controlling the flow of air through the transmission tube, a minimum flow of air through the tube being permitted when the valve is in closed position, a pneumatic for actuating said valve, said pneumatic being constantly exposed upon one side to full atmospheric pressure, a normally open passage admitting transmission tube pressure to act upon the opposite side of the pneumatic, and an auxiliary valve controlling said passage, said auxiliary valve remaining open while a carrier is in the tube and closing when the last carrier is delivered from the tube.

45. Pneumatic despatch apparatus having a transmission tube, an exhauster connected therewith and a valve for controlling the flow of air through the transmission tube, a minimum flow of air through the tube being permitted when the valve is in closed position, a pneumatic for operating the valve, said pneumatic being exposed on one side to atmospheric pressure, a passage admitting transmission line pressure to act upon the other side of the pneumatic, a normally open auxiliary valve controlling said passage, means for closing said auxiliary valve, said means tending to respond to decrease in transmission line pressure incident to insertion of a carrier in the transmission tube, the closing of said auxiliary valve being delayed

until the carriers are discharged from the tube, and means permitting pressure to equalize upon opposite sides of the pneumatic when the auxiliary valve is closed.

5. Pneumatic despatch apparatus having a transmission tube, an exhauster connected therewith, and a valve for controlling the flow of air through the transmission tube, a minimum flow of air through the tube being permitted when the valve is in closed position, a pneumatic for operating the valve, said pneumatic being exposed on one side to atmospheric pressure, a passage normally admitting transmission line pressure to act upon the other side of the pneumatic, an auxiliary valve controlling said passage, an auxiliary pneumatic responsive to decrease in pressure in the transmission tube for closing said auxiliary valve, and means actuated by the first named pneumatic for determining the time of closure of said auxiliary valve.

6. Pneumatic despatch apparatus having a transmission tube, an exhauster connected therewith, and a valve for controlling the flow of air through the transmission tube, a minimum flow of air through the tube being permitted when the valve is in closed position, a pneumatic for operating the valve, said pneumatic being exposed on one side to atmospheric pressure, a passage normally admitting transmission line pressure to act upon the other side of the pneumatic, an auxiliary valve controlling said passage, means tending to close the auxiliary valve upon insertion of a carrier in the transmission tube, and stop means actuatable by the main motor positively to prevent closure of the auxiliary valve until the carrier has emerged from the tube.

7. Pneumatic despatch apparatus having a transmission tube, an exhauster connected therewith, and a valve for controlling the flow of air through the transmission tube, a minimum flow of air through the tube being permitted when the valve is in closed position, and a pneumatic main motor for actuating the valve, said motor comprising a casing having a chamber therein, a flexible diaphragm forming one wall of said chamber, the outer surface of said diaphragm being exposed at all times to atmospheric pressure, means connecting the diaphragm to the valve, there being a passage normally open to admit transmission tube pressure to the chamber, an auxiliary valve for closing said passage, means tending to close said auxiliary valve when a carrier is introduced into the transmission tube, and means actuatable by the aforesaid diaphragm for delaying closure of said auxiliary valve until the carrier is discharged from the transmission tube.

8. Pneumatic despatch apparatus having a transmission tube, an exhauster connected therewith and a valve for controlling the flow of air through the transmission tube, a mini-

imum flow of air through the tube being permitted when the valve is in closed position, and a pneumatic main motor for actuating the valve, said motor comprising a casing having a chamber therein, a flexible diaphragm forming one wall of said chamber, the outer surface of said diaphragm being exposed at all times to atmospheric pressure, means connecting the diaphragm to the valve, there being a passage normally open to admit transmission tube pressure to the chamber, an auxiliary valve for closing said passage, means tending to close the auxiliary valve when a carrier is inserted in the transmission tube, and means actuatable by the main motor for delaying closure of the auxiliary valve until the carrier has been delivered from the tube, a restricted passage being provided to permit air to bleed into the motor chamber when the auxiliary valve is closed to equalize the pressure upon opposite sides of the diaphragm.

9. Pneumatic despatch apparatus having a transmission tube, an exhauster connected therewith and a valve for controlling the flow of air through the transmission tube, a minimum flow of air through the tube being permitted when the valve is in closed position, and a pneumatic main motor for actuating the valve, said motor comprising a casing having a chamber therein, a flexible diaphragm forming one wall of said chamber, the outer surface of said diaphragm being exposed to atmospheric pressure, means connecting the diaphragm to the valve, there being a passage normally open to admit transmission tube pressure to the chamber, an auxiliary valve for closing said passage, an auxiliary pneumatic for actuating the auxiliary valve, said auxiliary pneumatic tending to close said valve when transmission tube pressure drops below normal due to introduction of a carrier, and stop means actuatable by the aforesaid diaphragm for delaying closure of the auxiliary valve until the last carrier has been delivered from the transmission tube.

10. Pneumatic despatch apparatus having a transmission tube, an exhauster connected therewith, and a valve for controlling the flow of air through the transmission tube, a minimum flow of air through the tube being permitted when the valve is in closed position, a pneumatic main motor comprising a flexible diaphragm for operating the air controlling valve, said diaphragm being connected to said valve, an auxiliary valve for controlling pressure conditions in the pneumatic main motor, means including a reciprocating part tending to close the auxiliary valve when a carrier is inserted in the transmission tube, and a stop positionable to prevent movement of said reciprocating part, said stop being movable by the main motor diaphragm.

11. Pneumatic despatch apparatus having a transmission tube, an exhauster connected therewith and a valve for controlling the flow of air through the transmission tube, a minimum flow of air through the tube being permitted when the valve is in closed position, a pneumatic main motor for operating the air controlling valve, a normally open auxiliary valve for controlling pressure conditions in the pneumatic main motor, means tending to close the auxiliary valve when a carrier is inserted in the transmission tube, a normally inoperative stop for preventing closure of the auxiliary valve, and a part actuatable by the pneumatic main motor for setting said stop in operative position.

12. Pneumatic despatch apparatus having a transmission tube, an exhauster connected therewith and a valve for controlling the flow of air through the transmission tube, a minimum flow of air through the tube being permitted when the valve is in closed position, a pneumatic main motor for operating the air controlling valve, an auxiliary valve for controlling pressure conditions in the pneumatic main motor, a pneumatic auxiliary motor for actuating the auxiliary valve, said auxiliary motor comprising a casing having a chamber therein, a flexible diaphragm forming one wall of said chamber, the outer surface of said diaphragm being exposed to atmospheric pressure, means connecting said auxiliary motor diaphragm to the auxiliary valve, there being a restricted passage permitting slow transfer of transmission tube pressure to the chamber of the auxiliary motor whereby the diaphragm thereof tends to move and close the auxiliary valve when the pressure in the transmission line drops due to introduction of a carrier, and means actuatable by the main motor for delaying closure of the auxiliary valve until the carrier has emerged from the transmission tube.

13. Pneumatic despatch apparatus having a transmission tube, an exhauster connected therewith and a valve for controlling the flow of air through the tube, a minimum flow of air being permitted when the valve is in closed position, a pneumatic main motor for operating the air controlling valve, an auxiliary valve for controlling pressure conditions in the pneumatic main motor, a pneumatic auxiliary motor for actuating the auxiliary valve, said auxiliary motor comprising a casing having a chamber therein, a flexible diaphragm forming one wall of said chamber, a stem connecting the latter diaphragm with the auxiliary valve, said stem having a restricted axially extending passage permitting the slow transfer of transmission tube pressure to the chamber of the auxiliary motor whereby, upon decrease below normal in transmission tube pressure due to introduction of a carrier, the aux-

iliary motor diaphragm tends to move after a slight delay thereby to close the auxiliary valve, and stop means actuatable by the main motor for further delaying closure of the auxiliary valve until the carrier has been discharged from the tube.

14. Pneumatic despatch apparatus having a transmission tube, an exhauster connected therewith and a valve for controlling the flow of air through the transmission tube, a minimum flow of air through the tube being permitted when the valve is in closed position, a pneumatic main motor comprising a flexible diaphragm having a stem, means connecting one end of the stem to said valve, a normally open auxiliary valve for controlling pressure conditions in the pneumatic main motor, an auxiliary pneumatic for actuating the auxiliary valve, said auxiliary pneumatic having a stem connected at one end to the auxiliary valve, the auxiliary pneumatic tending to close the auxiliary valve when a carrier is inserted in the transmission tube, a stop lever positionable to prevent movement of the stem of the auxiliary diaphragm, and means normally holding said lever out of operative position, said lever being actuatable by the main motor to prevent closure of the auxiliary valve until the carrier has emerged from the transmission tube.

15. Pneumatic despatch apparatus having a transmission tube, an exhauster connected therewith, and a valve for controlling the flow of air through the transmission tube, a minimum flow of air through the tube being permitted when the valve is in closed position, a pneumatic for operating the valve, said pneumatic being exposed on one side to atmospheric pressure, a passage admitting transmission line pressure to act upon the other side of the pneumatic, an auxiliary valve controlling said passage, an auxiliary pneumatic responsive to decrease in pressure in the transmission tube for closing said auxiliary valve, and a movable stop positioned during flight of a carrier through the tube to prevent said auxiliary valve from closing but permitting said auxiliary valve to close when the carrier emerges from the tube.

16. Pneumatic despatch apparatus having a transmission tube, an exhauster connected therewith, and a valve for controlling the flow of air through the transmission tube, a minimum flow of air through the tube being permitted when the valve is in closed position, a pneumatic main motor comprising a flexible diaphragm having a stem, means connecting one end of the stem to said valve, a normally open auxiliary valve for controlling pressure conditions in the pneumatic main motor, an auxiliary pneumatic for actuating the auxiliary valve, said auxiliary pneumatic having a stem connected at one

end to the auxiliary valve, the auxiliary pneumatic tending to close the auxiliary valve when a carrier is inserted in the transmission tube, and a stop member actuatable by the diaphragm of the main motor, said diaphragm moving to its fullest extent and opening the main valve when a carrier is inserted in the transmission tube, said movement of the main diaphragm setting the stop to prevent movement of the auxiliary diaphragm, the main diaphragm returning part way to normal position when the carrier emerges from the tube and thereby resetting the stop to release the auxiliary diaphragm and permit the auxiliary valve to close.

17. Pneumatic despatch apparatus having a transmission tube, an exhauster connected therewith and a valve for controlling the flow of air through the transmission tube, a minimum flow of air through the tube being permitted when the valve is in closed position, a pneumatic main motor comprising a flexible diaphragm having a stem, means connecting one end of the stem to said valve, a normally open auxiliary valve for controlling pressure conditions in the pneumatic main motor, an auxiliary pneumatic for actuating the auxiliary valve, said auxiliary pneumatic having a stem connected at one end to the auxiliary valve, the auxiliary pneumatic tending to close the auxiliary valve when a carrier is inserted in the transmission tube, and a movable stop normally held in inoperative position against a limiting abutment by a spring, said stop being movable by the diaphragm of the main motor away from said abutment and into the path of the stem of the auxiliary diaphragm.

18. Pneumatic despatch apparatus having a transmission tube, an exhauster connected therewith, and a valve for controlling the flow of air through the transmission tube, a minimum flow of air through the tube being permitted when the valve is in closed position, a pneumatic main motor comprising a flexible diaphragm having a stem, means connecting one end of the stem to said valve, an auxiliary valve for controlling pressure conditions in the pneumatic main motor, an auxiliary pneumatic for actuating the auxiliary valve, said auxiliary pneumatic having a stem connected at one end to the auxiliary valve, the auxiliary pneumatic tending to close the auxiliary valve when a carrier is inserted in the transmission tube, a stop lever, a spring tending to swing the lever in one direction, an abutment for limiting such movement, means to adjust the tension of the spring and means for transmitting movement from the diaphragm of the main motor to the lever whereby to swing the latter away from its abutment and into the path of the stem of the auxiliary motor.

19. Pneumatic despatch apparatus having a transmission tube, an exhauster connected

therewith and a valve for controlling the flow of air through the transmission tube, a minimum flow of air through the tube being permitted when the valve is in closed position, a pneumatic main motor comprising a flexible diaphragm having a stem, means connecting one end of the stem to said valve, an auxiliary valve for controlling pressure conditions in the pneumatic main motor, an auxiliary pneumatic for actuating the auxiliary valve, said auxiliary pneumatic having a stem connected at one end to the auxiliary valve, the auxiliary pneumatic tending to close the auxiliary valve when a carrier is inserted in the transmission tube, and a stop lever swinging in the plane of movement of the stem of the auxiliary motor diaphragm and normally positioned to permit free movement of said stem, said lever being positionable by the main motor to prevent movement of the auxiliary diaphragm.

20. Pneumatic despatch apparatus having a transmission tube, an exhauster connected therewith and a valve for controlling the flow of air through the transmission tube, a minimum flow of air through the tube being

permitted when the valve is in closed position, a pneumatic main motor comprising a flexible diaphragm having a stem, means connecting one end of the stem to said valve, 30 an auxiliary valve for controlling pressure conditions in the pneumatic main motor, an auxiliary pneumatic for actuating the auxiliary valve, said auxiliary pneumatic having a stem connected at one end to the auxiliary 35 valve, the auxiliary pneumatic tending to close the auxiliary valve when a carrier is inserted in the transmission tube, the stems of the main and auxiliary motor diaphragm being substantially parallel, a stop lever 40 swinging in the plane of said stems, the opposite ends of the lever being disposed in the paths of the respective stems but normally out of contact with either, and means tending to retain the lever in normal position, movement of the stem of the diaphragm 45 of the main motor swinging the lever to prevent movement of the stem of the auxiliary motor.

Signed by me at Syracuse, New York, this 50 twenty-fifth day of March, 1925.

JAMES T. COWLEY.
